CONTROL APPARATUS

Arthur H. Buckley, Chicago, Ill.

Application August 30, 1939, Serial No. 292,584

4 Claims. (Cl. 176—124)

My invention relates in general to electrical controls, and has more particular reference to improved switch means especially well adapted for use in controlling gaseous conduction lamps.

An important object of the present invention is to provide compact and inexpensive switch means for controlling the delivery of electrical energy to an electrical device requiring, in addition to normal load energy, the delivery of energy to starting means for starting the device in 10 operation, such starting means being inactive during the operation of the device following the starting period.

A further object is to provide switch means, including a main switch element for controlling the delivery of load energy to an electrical device, an auxiliary switch element adapted to control the delivery of starting energy, and switch actuating mechanism mechanically interconnected with both the main and auxiliary switch elements for opening and closing the main switch and for causing the auxiliary switch to function as the main switch closes.

Another important object is to utilize a main switch and associated mechanism operable to place the main switch in either open or closed condition, and to arrange the mechanism so that the auxiliary switch will close and remain closed only during a starting interval after closure of the main switch, the auxiliary switch being adapted thereafter to open while the main switch remains closed so long as the device continues in operation.

Another object is to utilize an auxiliary switch, having means operatively associated with the main switch for allowing the auxiliary switch to close and remain closed for a period of time as an incident to the closure of the main switch; a further object being to utilize a switch operating mechanism for closing the main switch, in response to the application of switch actuating force or pressure, said mechanism functioning as an incident to the closure of the main switch to allow the auxiliary switch to remain in closed position so long as such actuating force is applied, and upon release of actuating pressure, to open the auxiliary switch and thus disable the starting means.

Another important object is to utilize, as switch actuating mechanism, means biased toward a normal or standby position and manually movable, by application of actuating pressure thereon, to a position permitting the auxiliary switch to remain closed only so long as actuating pressure is maintained upon the switch actuating

5 mechanism, the auxiliary switch being caused to open upon release of such actuating pressure; a further object being to arrange the switch actuated mechanism for the successive opening and closing of the main switch in response to successive applications of switch actuating pressure on said mechanism, whereby the sequence of operation of both the main and auxiliary switches is accomplished merely by the application and release of actuating pressure upon the switch actuating mechanism.

Another important object is to utilize a progressively acting device, such as a rotary switch, and to employ ratchet means for progressively operating the rotary switch to open and close the same; a further object being to provide cam means, under the control of said ratchet means, for actuating the auxiliary switch as an incident to the actuation of the main switch.

20 Another important object resides in the compact arrangement of main and auxiliary switches in a single unitary frame on which all of the parts of the main and auxiliary switches, and of the switch actuating mechanism, are mounted and retained; a further object being to form the frame as a mounting block, preferably of hard rubber, or other suitable insulating material, and to retain the parts in place on the block by a spring cover of simplified form.

25 Among the other numerous important objects of the invention is to provide a neat, compact pull switch construction for controlling electrical apparatus, having associated means requiring to be energized in order to start the device in operation; to provide switch mechanism, including a main switch for controlling the delivery of power to spaced electrodes of a gaseous conduction lamp, and an auxiliary switch mechanically interconnected with the main switch and operable 30 to energize lamp starting means during a limited period of time after the main switch has closed; to provide mechanism of a purely mechanical nature for actuating a plurality of interrelated switches for the purpose mentioned; 35 to reduce the cost of control mechanism for gaseous conduction lamps and similar equipment; and to provide simplified and inexpensive 40 pull switch means for controlling gaseous conduction lamps of the character described.

45 These and numerous other objects, advantages, and inherent functions of the invention will be apparent from the following description, which, taken in connection with the accompanying drawing, discloses a preferred embodiment of the invention.

Referring to the drawing:

Figure 1 is a diagrammatic view of a gaseous conduction lamp provided with control means embodying my present invention;

Figure 2 is an exploded view of parts comprising a preferred form of control means embodying my present invention;

Figure 3 is a sectional view taken through a control device embodying my present invention;

Figure 4 is a sectional view taken substantially along the line 4—4 in Figure 3; and

Figure 5 is a sectional view taken substantially along the line 5—5 in Figure 4.

To illustrate my invention, I have shown on the drawing an electrical device 11 adapted to receive electrical power from a suitable power source 13 through a control device 15 embodying my present invention and comprising a main switch 17. Upon the closure of the main switch, electrical power for the operation of the device 11 will be delivered thereto through the circuit comprising the conductors 19 and 21. The device 11 comprises starting means 23 requiring to be electrically energized in order to condition the device 11 for operation after closure of the switch 17, and consequently, the control device 15 embodies an auxiliary switch 25 connected to control the delivery of power to the starting means 23.

In the illustrated embodiment, the device 11 comprises a gaseous discharge lamp, and the starting means 23 comprise filaments adapted, when energized, to condition the gaseous medium in the lamp 11 for operation as a conduction medium. In gaseous lamps of the character mentioned, application of operating potential between the spaced filaments 23, by closure of the switch 17, will not necessarily start the lamp in operation unless the gaseous medium has been rendered sufficiently conductive to allow current to flow therethrough between the spaced electrodes 23 at the potential supplied by the source 13. The filaments 23, when energized, function to ionize the gaseous contents of the lamp to render the same conducting and thus condition the lamp for operation.

In the illustrated embodiment, the conductors 19 and 21 are connected each to one side of one of the filaments 23, a reactance, preferably in the form of a choke coil 28, being interposed in the conductor 19 in series with the gaseous conduction path. The other side of the filaments are interconnected in series through the auxiliary switch 25 so that upon closure of the switches 17 and 25, a series circuit may be established, including the power source, the filaments 23, and the switches 17 and 25, whereby thus to energize the filaments 23 in order to ionize and thus condition the gaseous contents of the lamp for operation.

In actual operation, the gaseous contents of the lamp become ionized almost instantaneously and consequently become conducting, but the lamp may not go into operation until the switch 25 is opened, since the resistance to current flow through the gaseous conducting path of the lamp, even when ionized, is substantially higher than the resistance of the circuit between the filaments 23 and including the switch 25. When the switch 25 is opened, however, the interruption in the circuit imparts an inductive voltage kick, by virtue of the coil 28, and, the gaseous conducting path being ionized, the lamp goes into operation by virtue of the series circuit, comprising the power source 13, the gaseous conduction

path of the lamp between the electrodes 23, and the closed switch 17, the filaments 23 acting as electrodes. The coil 28 also has a current limiting effect in the circuit.

It is the purpose of my present invention to provide improved and simplified control mechanism 15, including the main and auxiliary switches 17 and 25, whereby the main switch may be manually operated, as by means of the pull chain 27, to place the switch 17 either in open or in closed condition and thus control the delivery of operating power to the device 11. In order to provide a positive, preferably purely mechanical, and exceedingly simple and inexpensive mechanism, my invention contemplates the provision of means for closing the switch 25 and retaining the same in closed position for an interval after the closure of the switch 17 to allow the filaments 23 to perform their function in conditioning the gaseous conduction path of the lamp 11 for operation, and thereafter to open the switch 25 and allow the lamp to operate as such.

Of course, any suitable mechanical means for accomplishing the control of the switches 17 and 25 may be employed, and my present invention is not necessarily restricted to the particular form, construction or arrangement of the switches 17 and 25, or of the manually operable mechanism for actuating the same in the desired manner. In its broad aspect, my invention visualizes any suitable mechanical means for opening and closing the main switch, and for causing closure of the auxiliary switch only for a brief instant after the main switch has closed, and thereafter causing the auxiliary switch to open.

I prefer to accomplish the foregoing sequence of switch operation by manually operable means, including mechanism 29 adapted to be shifted in response to the application of switch actuating pressure thereon, whereby to successively open and close the main switch 17 in response to successive applications of switch actuating pressure on the mechanism, whereby the main switch is constituted as a successively and progressively operating switch device. The switch actuating mechanism also is arranged to cooperate with the auxiliary switch in order to cause closure of the same as and when the main switch is closed, the auxiliary switch remaining closed only for a short interval following closure of the main switch.

I prefer to constitute the main switch 17 as a rotary switch. Furthermore, I prefer to arrange the switch actuating mechanism in the form of pawl and ratchet means 31 and 33 drivingly connected with the main switch, the actuating mechanism 29 being also controllingly positioned with respect to the auxiliary switch, whereby the auxiliary switch is maintained normally in open position by said actuating mechanism. The actuating mechanism is also arranged to release the auxiliary switch for closure thereof as the mechanism is moved to actuate the main switch, said auxiliary switch remaining in closed position until the mechanism is relieved of switch actuating pressure and permitted to return to a position in which it again holds the auxiliary switch in open position.

As shown in the illustrated embodiment, more particularly in Figure 2, the main and auxiliary switches and the actuating mechanism may be supported on a frame 35, which may conveniently be formed of molded rubber or similar insulating material. The main switch 17 may comprise a pair of stationary spring contacts 37,

which may be conveniently arranged in cavities 39 formed for the purpose in the frame 35, said contacts being electrically connected in the cavities 39 with the conductors 21 comprising cables extending outwardly of the frame 35. The frame 35 also provides a space 41 therein intermediate the cavities 39, in which space 41 is mounted a turnable switch member comprising, in the illustrated embodiment, a quatrefoil star wheel 43, having a central, non-circular, preferably square opening 45 for the reception of a driving pin 47. The star wheel carries thereon a circuit making contact element 49, having legs adapted to overlie two of the opposing four surfaces of the star wheel, so that when said surfaces are in engagement with the spring contacts 37, the member 49 will complete electrical connection between the spring contacts, but when the star wheel is rotated to position in which the remaining two surfaces of the star wheel are in contact with the spring contacts 37, the circuit between said contacts will be open. An insulating piece 51 is disposed in the frame 35 above the star wheel and the contacts, the pin 47 extending in the cavity 45 to drivingly connect with the star wheel, and extending through a central opening 53 in the insulating plate 51 and upwardly thereof. It will be seen that by turning the stem 47 upwardly of the plate 51, the star wheel 45 may be turned between the contacts 37 to alternately make and break the electrical connection between the switch contacts 37.

The ratchet 33 comprises a preferably metal disk 55, having a central squared opening 57, receiving the driving pin 47 above the disk 51. The ratchet disk 55 is provided with four peripherally arranged slots 59.

The pawl 31 preferably comprises a sheet metal member, having a plate portion 61 adapted to overlie and ride upon the ratchet plate 55, said plate portion 61 having a struckout ratchet detent 63, preferably at the edge of the portion 61, in position to engage the openings 59 of the plate 55. The plate portion 61 also has a central opening, preferably defined by an upstanding rim 65, which opening is adapted to receive and rotate on the pin 47. The pawl member also is preferably provided with integral upstanding ears 67 at the edges of the plate portion 61 and subtending substantially one-half of the circumference of the portion 61, said ears 67 forming a trackway for receiving the pull chain 29, the end link of which may be anchored in a slot 69 formed at an end of one of the ears 67.

The parts are held in place in the frame 35 by means of a holding arm 71, having a portion 72 adapted to extend in and be anchored in a slot 73 formed in the frame 35. The holding member 71 has an arm 76 extending in position above the pin 47, said arm 76 having a depending prong 77 in position to be received axially in an axial channel 79 formed in the pin 47. The prong 77 and the portions of the pin 47 which extend upwardly through the collar 65 provide a mounting for a biasing spring 81, one end of which is hooked upon the arm 76, and the other end of which is hooked for engagement with an edge of an ear 67 adjacent the ratchet detent 63, whereby the spring 81 normally urges the pawl member 31 on the pin 47 in a counter-clockwise direction, viewing Figure 5 of the drawing, the counter-clockwise movement of the pawl member 31 being limited by

the engagement of the end ball of the pull chain with the base of the retaining member 71.

The auxiliary switch 25 comprises a pair of switch elements 83 and 85 mounted upon the frame 35, as in a cavity 87 formed at the back of the frame, the switch arms 83 and 85 being of electrical conducting material and having ends 89 exposed outwardly of the frame and formed for connection with the conductors 26. The arms 83 and 85 are insulated the one from the other, as by means of a suitable insulating block 91, and the free ends of the arms may be provided with contact buttons 93 in opposing registration. The arm 85 has sufficient resilience to normally hold the contact buttons in engagement, whereby to close the switch, said arm, however, at its end is provided with a finger 92 extending through an opening 95 in the frame 35 so that the finger 92 may rest upon the ear 67 adjacent the chain anchorage 69 when the pawl is in the normal stopped position, as shown in Figure 5 of the drawing. So long as the pawl is in such stopped position, it will hold the switch 25 in open position.

The switch parts are enclosed, and the pawl and ratchet mechanism retained in the frame 35 by means of a preferably sheet metal cover 97, comprising an end wall 99 adapted to overlie the cavity 87 housing the switch 25, the top wall 101 overlying the pawl and ratchet mechanism and the holding member 71 to retain the same in place in the frame, an end wall 103 overlying the front of the frame and provided with a chain outlet 105. The cover 97 also may be formed with edge lugs 107 to prevent lateral displacement thereof on the frame, and holding lugs 109 to engage the under side of the frame and hold the cover in place.

When switch actuating pressure is applied on the mechanism 29, as by pulling the chain 27, the pawl member 31 is rotated from the normal or inactive position, shown in Figure 5, in a clockwise direction until stopped by the engagement of the end of the chain track forming ear means 67 with the stop forming portions of the member 71, the spring 81 being tensioned by such movement. As soon as the pawl 31 moves from the normal position, shown in Figure 5, the edge of the ear means 67 adjacent the chain anchorage 69 is moved away from switch finger 92, thus permitting the switch 25 to close. At the same time, the pawl portion 63 catches in one of the openings 59 of the ratchet disk and causes the driving stem 47 to be turned, by virtue of the splined relationship of the stem in the opening 57 of the pawl disk. The stem 47, in turn, rotates the switch member 43 and causes switch 17 to move from closed to open, or from open to closed position. The switch 25, of course, remains closed, due to the inherent resilience of the arm 85 or other switch closing means as may be employed within the purview of my present invention, until switch actuating pressure on the pawl is relieved, as by releasing the pull chain 27. As soon as the pull chain is released, the spring 81 causes rotation of the pawl member 31 in counterclockwise direction to retract the same to the normal position shown in Figure 5, thus opening the switch 25 and conditioning the pawl to throw the switch 17, as a result of a succeeding pull on the chain, the switch 25 remaining open until the pawl is again actuated.

I prefer to connect a condenser 111 of small capacity across the switch 25, and this condenser 111 may be conveniently mounted, as shown in

the cavity 87, immediately below the contacts 83 and 85 forming the switch 25.

It will be seen from the foregoing that I have provided control mechanism of a purely mechanical and positive character. The construction is neat, compact, and extremely inexpensive, in comparison with contraptions of an electromagnetic or thermal relay type heretofore provided for the accomplishment of the switch operation. In operation, however, the device of my present invention is direct and positive, substantially noiseless, and, in addition to its cost advantages, eliminates all of the operating disadvantages of non-positive relay type equipment.

It is thought that the invention and its numerous attendant advantages will be understood from the foregoing description, and it is obvious, of course, that numerous changes may be made in the form, construction, and arrangement of the several parts without departing from the spirit and scope of the invention or sacrificing any of its attendant advantages.

The invention is hereby claimed as follows:

1. The combination, with a main switch and an auxiliary switch for controlling a gaseous conduction device having a pair of spaced filamentary electrodes, of means for connecting said main switch in circuit to control the delivery of electric potential between said electrodes from a suitable power source, said auxiliary switch being adapted for connection between said filamentary electrodes to control the flow of electric current therethrough, a member drivingly connected with both switches and manually operable in one direction to close the main switch, and spring means connected to move said member in the opposite direction to open the auxiliary switch upon manual release of said member, following closure of the main switch, whereby both switches may be closed for a predetermined interval under manual control, and the auxiliary switch opened upon release of said manual control.

2. The combination, with a main switch and an auxiliary switch for controlling a gaseous conduction device having means forming spaced electrodes and an ionizing filament, of means for connecting said main switch in circuit to control the delivery of electric potential between said electrodes from a suitable power source, means to connect said auxiliary switch to control the flow of electric current through said filament from a suitable source, a member drivingly connected with both switches and manually operable in one direction to close the main switch, and spring means connected to move said member in the opposite direction to open the auxiliary switch upon manual release of said member, following closure of the main switch, whereby both switches may be closed for a predetermined interval under manual control, and the auxiliary switch opened upon release of said manual control.

3. The combination, with a main switch and an auxiliary switch, of a rotatable switch element rotatable in one direction to alternately open and close the main switch, ratchet means connected on the rotatable switch element, a reversely movable pawl element comprising actuating means manually operable in one direction from a starting position and comprising a pawl in position to engage said ratchet means to move said rotatable switch element, a retracting spring connected to return said actuating means to said starting position when manually released, and auxiliary switch driving means comprising a portion formed on said pawl means and co-operating means connected to said auxiliary switch, said portion and said co-operating means being positioned for co-operative engagement, during the switch operating cycle of said pawl means, whereby said auxiliary switch may be closed when the main switch is closed by manual operation of said actuating means, said auxiliary switch being adapted to remain closed so long as manual switch actuating pressure is maintained on said actuating means against the urge of said retracting spring means, said auxiliary switch driving means operating to open said auxiliary switch in response to reverse movement of said actuating means under the influence of said spring means upon the manual release of said actuating means following closure of the main switch.

4. The combination, with a main switch and an auxiliary switch, of a rotatable switch element rotatable in one direction to alternately open and close the main switch, a ratchet on the rotatable switch element, a reversely movable actuating element having pawl means thereon in position to engage said ratchet, said actuating element being manually operable in one direction from a starting position to advance said rotatable switch element, retracting spring means connected to return said actuating element to said starting position when manually released, and an auxiliary switch driving member on said actuating element and a co-operating member connected to said auxiliary switch, said driving and co-operating members being positioned for co-operative engagement at intervals during the switch operating cycle of said reversely movable actuating element whereby said auxiliary switch may be closed when the main switch is closed by manual operation of said actuating element, said auxiliary switch being adapted to remain closed so long as manual switch actuating pressure is maintained on said actuating element against the urge of said retracting spring means, said auxiliary switch actuating means operating to open said auxiliary switch in response to reverse movement of said actuating element under the influence of said spring upon the manual release of said actuating element following closure of the main switch.

ARTHUR H. BUCKLEY.
